[57] **CLAIM**

The ornamental design for closed disposable package, as shown and described.

DESCRIPTION

FIG. 1 is a perspective view of a closed disposable package showing our new design;
 FIG. 2 is a front view thereof;
 FIG. 3 is a top view thereof;
 FIG. 4 is a bottom view thereof;
 FIG. 5 is a back view thereof;
 FIG. 6 is a left side view thereof;
 FIG. 7 is a right side view thereof;
 FIG. 8 is a perspective view of another embodiment of closed disposable package;
 FIG. 9 is a front view thereof;
 FIG. 10 is a top view thereof;
 FIG. 11 is a bottom view thereof;
 FIG. 12 is a back view thereof;
 FIG. 13 is a left side view thereof; and,
 FIG. 14 is a right side view thereof.
